UNITED STATES PATENT OFFICE.

JAMES RATLIFF YEARWOOD, OF LIMA, OHIO.

UNLOADING DEVICE.

1,258,078.

Specification of Letters Patent.

Patented Mar. 5, 1918.

Application filed August 9, 1917. Serial No. 185,350.

To all whom it may concern:

Be it known that I, JAMES RATLIFF YEARWOOD, a citizen of the United States, residing at Lima, in the county of Allen and State of Ohio, have invented certain new and useful Improvements in Unloading Devices; and I do declare the following to be a full, clear, and exact description of the invention, such as will enable others skilled in the art to 10 which it appertains to make and use the same.

My invention has for its object to provide a simply constructed and inexpensive, yet a highly efficient and durable device for unloading railway cars and barges, and with this general object in view, the invention resides in the novel features of construction and unique combination of parts to be hereinafter fully described and claimed, the descriptive matter being supplemented by the accompanying drawings which form part of this specification and in which:

Figure 1 is a perspective view of the invention before the scoop is loaded, and

Fig. 2 is a similar view after loading and raising of the scoop.

In the drawing above briefly described the numeral 1 designates a horizontal supporting bar adapted to rest on the upper edge of a car body or barge, suitable clamps 2 being provided for securing said bar in place. To prevent possible upward tilting of the bar 1, a hook or the like preferably depends therefrom for passage under the car or barge, a turnbuckle 4 being shown for drawing the bill of the hook to operative position.

The outer end of the bar 1 extends beyond the body of the car or barge and is provided with a stub 5 upon which a vertical swinging lever 6 is fulcrumed between its ends, one end of said lever being directed laterally as shown at 7 to overlie the body of the car or the like, whereas the other end 8 of the lever 6 preferably inclines downwardly from the body portion thereof. The laterally extending end 7 carries a sheave 9 or other appropriate cable guide whereas a similar guide 10 is mounted on the opposite end of said lever, while two or more additional guides 11 are by preference employed at the two angles.

A cable 12 is trained around the guides 9, 10 and 11, and at one end is secured to a bucket 13 which is shown in the form of a common type of scoop. The other end of

the cable 12 passes around a pulley or the like 14 which is spaced from the guide 10 and located in the plane of movement of the lever, said cable also passing around another pulley 15 and then continuing to any suitable pulling means such as a windlass or a snatch team. The pulley 14 will in most cases be provided with a chain or other suitable anchor 16 by which it may be secured to the draw bar B when the device is employed upon a railway car, said anchor serving the same function when the improved mechanism is used on a barge, it being necessary, however, to secure said anchor to another appropriate part. The pulley 15 is mounted on a suitable block 17 having a chain or the like 18 by which it may be anchored to one of the rails of a track or to another suitable relatively fixed member, the block 17 also carrying an additional pulley 15' whose function will hereinafter appear.

As shown clearly in Fig. 1, the lever 6 is normally positioned in substantial and horizontal plane with its lateral directed end 7 resting upon the upper edge of the barge or car body, said lever being held in this position by any preferred means such as the bolt 19 illustrated in the drawings, said bolt being shown mounted upon an appropriate clamp 20 whereby it may be attached and detached as occasion may demand when the cable 12 has been pulled to the required extent, however, to load the scoop 13 and to draw this scoop to the end 7 of the lever 6, the bolt 19 will be released either by hand or otherwise, so that a further pull upon the cable will move the end 8 of the lever toward the pulley 14. In so moving, the lever 6 raises the loaded scoop above the edge of the barge or car so that it may be dumped upon a chute 21 to load the material into a wagon or the like provided for the purpose. The chute 21 is preferable secured to the bar 1 but it might obviously be mounted in any other preferred manner or the lever 6 could be of such construction as to permit its lateral end 7 to swing beyond the car or barge so that the scoop 13 could be dumped directly into a wagon or the like without the necessity of employing a chute.

Any preferred means could well be employed for returning the scoop 13 to any required point within the car or barge, but for this purpose I preferably employ a second cable 22 which is secured at one end to the scoop 13 whereas the other end of said cable

- passes around the pulley 15' and leads to a windlass or any other preferred means which may be employed for pulling upon said cable when required. The intermediate portion of 5 cable 22 is trained around a pair of guide pulleys 23 preferably having clamps 24 by means of which they may be secured to and adjusted along the end of the barge or car remote from the lever 6.
- 10 From the foregoing, taken in connection with the accompanying drawings, it will be obvious that I have provided a comparatively simple and inexpensive arrangement of parts for carrying out the object of the invention, yet that the device will be highly 15 efficient and durable for the two uses specified as well as for any other purpose to which it may be found applicable. On account of the several advantages resulting from the 20 features of construction shown and described, this construction constitutes the preferred form of the improved unloading device but I wish it understood that within the scope of the invention as claimed, numerous 25 minor changes may well be made without sacrificing the principal advantages. Furthermore the invention is not restricted in use to any particular field, but may be used for the unloading of cars, barges, storage bins, 30 etc., and for excavating or removing all sorts of material. The device may be mounted on either a fixed or movable object and may be operated by windlass, horse power, gasolene or steam power, electricity, etc.
- 35 I claim:—
1. In a hoisting device, the combination of a support, a lateral projection extending horizontally from said support, a vertically swinging lever fulcrumed between its ends 40 on said projection and normally disposed in substantially a horizontal position, one arm of said lever being extended laterally in a horizontal direction at a point spaced from the fulcrum, a pulley at each end of said 45 lever and one at the angle thereof, a hoisting cable trained around said pulleys and depending from the lateral end of said lever, and means on said depending cable end for engagement with the material to be hoisted, 50 the other end of said cable being adapted to be pulled, whereby to raise the load to the lever and to then swing said lever to a substantially vertical position.
  2. In a hoisting device, the combination of a horizontal bar and means for securing it to a box with one end extending therefrom, a vertically swinging lever fulcrumed between its ends on said end of said bar, one arm of said lever being extended laterally in a horizontal direction at a distance from the fulcrum and located in substantially parallel relation with said bar, whereby to overlie the upper edge of the box and limit the swinging movement of the lever in one direction, pulleys on the ends of said lever and at the angle thereof, a hoisting cable trained around said pulleys and depending from the lateral end of said lever, and means on the depending cable end for engagement with the material to be hoisted, the other end of said cable being adapted to be pulled, whereby to raise the load to the lever and to then swing said lever to a substantially vertical position.
  3. In a hoisting device, the combination of a box having an open top and containing the material to be hoisted, a horizontal bar secured to the upper edge at one side of said box and projecting beyond one end thereof, a vertically swinging lever fulcrumed between its ends to the projecting end of said bar, said lever operating in a plane parallel to said end of the box and having one of its ends bent laterally to position its terminal above the box, said laterally bent end normally resting on the upper edge of said end of the box to limit the movement of the lever in one direction, releasable means for holding said lever in this position, a pulley at each end of said lever, other pulleys at the angle of said lever and adjacent the fulcrum thereof, a hoisting cable trained around said pulleys, and a bucket secured to the end of said cable adjacent said lateral end of the lever, the other end of said cable being adapted to be pulled to raise the loaded bucket against the lever and to swing said lever to substantially a vertical position when the holding means thereof is released.

In testimony whereof I have hereunto set my hand in the presence of two subscribing 100 witnesses.

JAMES RATLIFF YEARWOOD.
